UNITED STATES PATENT OFFICE.

YURAJ DEDIK, OF BOSWELL, PENNSYLVANIA.

SHIP-PROTECTOR.

1,397,405.

Specification of Letters Patent.

Patented Nov. 15, 1921.

Application filed June 11, 1920. Serial No. 388,114.

To all whom it may concern:

Be it known that I, YURAJ DEDIK, a citizen of Czechoslovakia, residing at Boswell, in the county of Somerset and State of Pennsylvania, have invented certain new and useful Improvements in Ship-Protectors, of which the following is a specification.

This invention relates to certain new and useful improvements in ship protectors particularly serviceable for preventing capsizing of vessels in heavy seas and also of value in receiving shocks of collisions so as to minimize danger of damage to the hull of the vessel.

15 The invention broadly consists in an endless hollow float loosely surrounding the hull of the vessel and associated with mechanism for normally holding it raised in an inoperative position and for permitting the 20 same to lower to an operative position when required for use.

The objects of the invention are preferably carried out by the construction hereinafter more fully described, shown in the 25 accompanying drawings and claimed.

In the drawings forming a part of this application, and in which like reference characters designate corresponding parts throughout the several views,

30 Figure 1 is a side elevational view of a vessel equipped with a protector constructed in accordance with the invention,

Fig. 2 is a top plan view thereof,

Fig. 3 is a transverse sectional view taken 35 substantially upon line III—III of Fig. 4,

Fig. 4 is a fragmentary top plan view of the device shown in Fig. 2, with the cabin of the vessel in horizontal section, and drawn on a larger scale,

40 Fig. 5 is a transverse sectional view taken substantially upon line V—V of Fig. 4,

Fig. 6 is an enlarged detail view, partly in elevation, and partly in section, and illustrating the clutch mechanism for rendering the protector raising mechanism inoperative at will, and

Fig. 7 is a sectional view taken substantially upon line VII—VII of Fig. 6.

Referring more in detail to the several 50 views, the present invention includes an endless hollow float 5 constructed of metal or any other desirable material and conforming to the shape of the ship hull 6 as well as extending entirely around the latter 55 at a point adjacent the water line of said hull.

A pair of vertical rack bars 7 are rigid with and extend upwardly from the floats 5 at each side of the hull 6 and pinions 8 are rotatably mounted upon the deck of the 60 vessel so that one pinion meshes with each rack 7. Another rack bar 9 is rigid with and extends upwardly from the float 5 at the rear of the vessel while a similar rack bar 10 is carried by the float at the forward 65 end of the vessel and these rack bars 9 and 10 each mesh with an idler pinion 11 suitably rotatably mounted upon the adjacent portions of the deck of the vessel. The rack bars 9 and 10 and idler pinions 11 are 70 merely provided to steady the float in operation and to effectively guide the float when being raised or lowered so as to minimize friction.

Each pinion 8 has a bevel gear 12 rigid 75 therewith and meshing with another bevel pinion 13 fastened upon a transversely arranged shaft 14 which extends into the cabin 15. It will thus be seen that the forward pair of pinions 8 are operatively geared to 80 a pair of shafts 14 which extend inwardly toward each other, while the rear pair of pinions 8 are similarly geared to a pair of shafts 14 that also extend transversely of the vessel inwardly toward each other 85 within the cabin 15.

A suitable motor 16 is mounted in the cabin between the pairs of shafts 14, and each pair of the latter are operatively geared to the shaft 17 of this motor by 90 similar mechanism which is best illustrated in Figs. 3 to 5 inclusive. This involves a system of gearing 18 suitably mounted at each side of the motor 16 and involving four spur gears which mesh with each other, 95 three of which are of the same size and the other of which is larger and fastened upon the motor 17. The end spur gears of each system of gearing have miter gears 19 fastened upon the shafts thereof and each 100 miter gear 19 meshes with a similar gear 20 fastened upon the inner ends of the adjacent shaft 14. A suitable clutch 21 is provided upon each shaft 14 for connecting and disconnecting the miter gear 20 thereof to 105 the same at will so as to control the transmission of power from the motor 16 to a desired one or all of the pinions 8 when found necessary. Each clutch 21 is provided with an ordinary operating lever 22 so that the 110 same may be readily manipulated.

In operation, the motor 16 is started for

rotating its shaft 17 in one direction and, through the gearing described, the pinions 8 are rotated for causing upward movement of the rack bars 7 simultaneously so that the 5 float 5 is brought to an inoperative position as shown by full lines in Fig. 3 above the water line of the hull 6. When it is desired to place the float 5 in use, the clutches 21 may be disconnected so that the float will 10 lower by gravity until it strikes the water whereupon the clutches 21 may be again connected for maintaining the float in its operative position which is indicated by dotted lines in Fig. 3. However, if, for 15 any reason, resistance is offered to the lowering of the float 5, by gravity, the clutches 21 may be operated for connecting the miter gears 20 to the shafts 14 and the motor 16 may then be started so as to rotate 20 its shaft in a reverse direction for causing the rack bars 7 to be moved downwardly so as to force the float to its operative position.

It will be obvious that when the float 5 is lowered upon the water, the same will effectively serve as a buoy and greatly lessen the danger of capsizing of the vessel in rough or heavy seas, and should a collision occur, the float will receive the impact and 30 damage before damage can be done to the hull of the vessel at its water line.

It is believed that the construction and operation of the present invention as well as the advantages of the same will be readily appreciated and understood by those skilled 35 in the art and minor changes may be made therein without departing from the spirit and scope of the invention as claimed.

Having thus described my invention what I claim as new and desire to secure by Letters Patent is:

A ship protector comprising in combination with a vessel, an endless horizontally disposed hollow float conforming to and extending entirely around the hull of the vessel adjacent the waterline thereof, forward and rear pairs of rack bars rigid with and extending upward from the float at the opposite sides of the hull, pinions meshing with said rack bars and mounted on the deck of the vessel, a motor mounted on the deck of the vessel and having a drive shaft extending forwardly and rearwardly, driving connections between each pair of pinions and one end of said drive shaft, and means 55 to render said driving connections inoperative at will, whereby raising of said float from operative to inoperative position may be had.

In testimony whereof I affix my signature. 60

YURAJ DEDIK.
